Inventor:

Nathan Lawrence

United States Patent Office.

NATHAN LAWRENCE, OF TAUNTON, MASSACHUSETTS.

Design No. 3,481, dated May 11, 1869.

DESIGN FOR AN ICE-PITCHER.

The Schedule referred to in these Letters Patent and making part of the same

To all whom it may concern:

Be it known that I, NATHAN LAWRENCE, of Taunton, in the county of Bristol, and State of Massachusetts, have invented a new and useful Design for a Double-Wall Ice-Pitcher, of which the following is a full, clear, and exact description, reference being had to the accompanying drawings, making a part of this specification, in which the drawing is a perspective view.

This design contemplates a four-sided double-wall ice-pitcher, with rounded corners, two of the opposite

sides being wider than the other two opposite sides, and the pitcher being thus oblong in cross-section.

Having thus described my invention, What I claim as new, and desire to secure by Letters Patent, is—

The design of an oblong shape, when applied to the body of a double-wall ice-pitcher.

NATHAN LAWRENCE.
